UNITED STATES PATENT OFFICE

WALTER DORNING, OF BERLIN-DAHLEM, GERMANY

CONSTANT-SPEED MULTIFREQUENCY ELECTRICAL GENERATING APPARATUS

Application filed January 8, 1929, Serial No. 331,100, and in Germany November 28, 1928.

My invention relates to a constant speed multi-frequency electrical generating apparatus. It is known that with the aid of different transmission frequencies, a plurality 5 of telegrams can be sent simultaneously through a conducting cable, for which purpose, ten separate valve generators, for example, with the frequencies 300-400-500 etc. periods, were employed. The use of valves is 10 very expensive because of the necessity for repeated renewals and a machine for generating the frequencies is therefore preferable from an economic standpoint.

The possibility of using a machine instead 15 of valves however is dependent upon the generation of constant frequencies and freedom from oscillations from harmonics comparable at least to that of the valves or better.

Multi-frequency generators for this purpose 20 have been proposed in various forms, but the machines heretofore developed have proved objectionable for different reasons, and this invention provides an improved machine or generating apparatus of the stated 25 character in combination with means for maintaining the speed of the generators constant.

The invention will be best understood by 30 description with reference to the attached drawings, wherein one practicable embodiment thereof is shown by way of example.

In said drawings a constructional form of 35 generating plant or apparatus adapted for ten different frequencies is shown in a somewhat diagrammatic manner and in part section as viewed from the side.

The illustrative generator is of the equi-polar inductor type, with the particular feature according to this invention that all the 40 frequencies (i. e. the ten different frequencies) are obtained from the same machine, or in other words, ten separate generators are combined in the same casing and receive flux from a common excitation winding arranged 45 co-axially with the generator shaft. In this generator, 1 is the casing, 2^a to 2^k are the stators of different sizes but of substantially equal internal diameters fitted with their 50 slots and windings, and 3^a to 3^k are the corresponding rotors of different sizes and sub-

stantially equal outer diameters. Hence 2^a plus 3^a, or 2^b plus 3^b, and so on, form separate generators, while 4 is the common excitation winding. In this instance, the stators and rotors of the separate generators or units 55 are of increasing size or iron breadth as they are located successively further from said winding on both sides of the latter. The several generators situated on each side of the excitation winding form parallel magnetic 60 paths, and according to my invention, the reluctances of these paths are (under maintenance of the rotors of substantially the same diameter) made equal by gradually increasing the iron breadths of the generators, the 65 more remote they are from the common excitation winding. The flux moreover may be brought to the optimum value by judicious selection or regulation of the air gaps between their stator and rotor elements, or more 70 specifically by making the air gap dimensions between said co-operative elements narrower as they are further removed from the excitation winding, as indicated in the drawing. As a matter of principle it is also possible, 75 of course, to dispose all the separate generators on one side only of the excitation winding. If a very large number of frequencies be required, such as twenty, it becomes a matter for consideration whether a single excitation coil will suffice, and in certain circumstances, a separate source of flux may be employed for each large group, such as each group for ten frequencies.

In order to maintain a constant speed, or 80 constancy of frequency, the driving motor 5 is controlled by any kind of device for maintaining constant speed and preferably by the centrifugal governor 6 represented diagrammatically in the drawing as described, 85 for example, in the Elektrotechnische Zeitschrift, 1928, No. 47, p. 1713. A multi-frequency generator constructed on the foregoing principles and operated in conjunction with a constant speed device gives particularly 90 good performance, especially as regards the even contour of the curves which are obtained without any mutual interference between the various frequencies.

These multi-frequency generators are also 100

specially adapted as common sources of supply to the test benches in cable works, etc., where the usual measuring frequencies of 5000, 7000, 10000, 14000 and 20000 omega $(=\omega=2\pi\sim)$ are mostly employed.

In practice, this converter is preferably so constructed that the generator 1, motor 5, and constant-speed governor 6 and all located in a common housing.

Having now fully described my invention, what I claim and desire to secure by Letters Patent is:—

1. A multi-frequency electrical generating apparatus, comprising a multi-frequency generator of the homopolar inductor type having a plurality of independent stator-rotor units of substantially the same diameter; an excitation winding common to all of said units for providing magnetic flux therefor; means for driving said generator; and means for controlling the speed thereof; the air gap distances between successive co-operating rotor and stator units being decreased progressively from the units nearest the exciting winding to those furthest from it, thereby adapting them to independently generate different frequencies.

2. A multi-frequency electrical generating apparatus, comprising a multi-frequency generator of the homopolar inductor type having a plurality of independent stator-rotor generating units of substantially the same diameter combined in a single housing; an excitation winding common to the plurality of said units for providing magnetic flux therefor; means for driving said generator, and means for controlling the speed thereof, the stator and rotor elements of the several units being of different iron breadth increasing as the units are located successively further from the excitation winding and the air gap distances between successive co-operating rotor and stator units being progressively decreased from the units nearest the exciting winding to those furthest from it, thereby adapting them to independently generate different frequencies.

3. A multi-frequency electrical generating apparatus, comprising a multi-frequency generator of the homopolar inductor type having a plurality of independent stator-rotor generating units of substantially the same diameter; an excitation winding common to the plurality of said units for providing magnetic flux therefor; means for driving said generator, and means for controlling the speed thereof, the cooperative stator and rotor elements of the several units being of differing size or breadth and having air gap distance therebetween decreasing progressively as they are located successively further from the excitation winding, thereby adapting them to independently generate different frequencies at a constant rate with constant drive speed.

4. A multi-frequency electrical generating apparatus, comprising a multi-frequency generator of the homopolar inductor type having a plurality of independent stator-rotor generating units of substantially the same diameter combined in a single housing; an excitation winding common to the plurality of said units for providing magnetic flux therefor; means for driving said generator, and means for controlling the speed thereof, the cooperative stator and rotor elements of the several units being of successively different iron breadth increasing as the units are located further from the excitation winding, thereby adapting them to independently generate different frequencies.

In testimony whereof I affix my signature.

WALTER DORNIG.
